UNITED STATES PATENT OFFICE.

NAPOLEON LODOR, OF RICHMOND, VIRGINIA.

DESIGN FOR AN INGOT.

SPECIFICATION forming part of Design No. 34,346, dated April 9, 1901.

Application filed March 6, 1901. Serial No. 50,143. Term of patent 14 years.

To all whom it may concern:

Be it known that I, NAPOLEON LODOR, a citizen of the United States, residing at Richmond, in the county of Henrico and State of Virginia, have invented and produced a new and original Design for an Ingot; and I do hereby declare the following to be a full, clear, and exact description of the same, reference being had to the accompanying drawings, forming a part thereof.

Figure 1 is a perspective view of my new design of ingot. Fig. 2 is a cross-section on the line 2 2 of Fig. 1. Fig. 3 is a longitudinal section on the line 3 3 of Fig. 1. Fig. 4 is an inverted plan view thereof.

As shown in the drawings, my design consists of an elongated body having parallel sides *aa*, that merge with semicircular ends *b*.

At the side and end edges the top has an annular flange *c*, and centrally the top has an ornamental raised surface *d*, the upper face of which is in a plane with the upper surface of the flange *c*, and at each end between the

end of the part *d* and the rounded ends *b* the top has a circular depression *e*. 25

The sides and ends of the body are inclined or tapered outward, as best shown in Figs. 2 and 3 and indicated by *f* and *g*, and the bottom of the ingot has the external contour of the top, the flanges *b'*, however, only extending around the semicircular ends, and said flanges *b'* terminate with a flat bottom surface *h*, that lies in a plane with the bottom surface of the flanges *b'*. 30

Having thus described my invention, what I claim, and desire to secure by Letters Patent, is—

The design for an ingot, substantially as herein shown and described.

In testimony whereof I affix my signature in presence of two witnesses.

NAPOLEON LODOR.
